Primary Examiner—A. Hugo Word*Assistant Examiner*—M. Brown*Attorney, Agent, or Firm*—Knobbe, Martens, Olson & Bear[57] **CLAIM**

The ornamental design for the exhaust system pressure control, as shown and described.

DESCRIPTION

FIG. 1 is a perspective view of an exhaust system pressure control showing my new design;

FIG. 2 is a front view of the exhaust system pressure control of FIG. 1;

FIG. 3 is a cross-sectional view taken along 3—3 of FIG. 2;

FIG. 4 is a back view of the exhaust system pressure control of FIG. 1; and,

FIG. 5 is a side view of the exhaust system pressure control of FIG. 1.

FIG. 1

FIG. 3

FIG. 5

FIG. 2

FIG. 4
